UNITED STATES PATENT OFFICE

CHARLES LORBER, OF LOUISVILLE, KENTUCKY

ICE PICK

Application filed October 6, 1930. Serial No. 486,754.

This invention relates to household articles and has special reference to a combined ice pick and bottle opener.

One important object of the invention is to provide an improved general construction of devices of this character.

A second important object of the invention is to provide a novel device of this kind having a bottle opener at one end of a shank and an ice pick point at the other, the shank having a sliding handle thereon for striking blows on the pick and for obtaining leverage on the bottle opener.

With the above and other objects in view, as will be hereinafter described, the invention consists in general of certain novel features of construction and combinations of parts described fully, illustrated in the accompanying drawing and specifically claimed.

In the accompanying drawing like characters of reference indicate like parts in the several views, and:

Figure 1 is a longitudinal section through one form of pick constructed in accordance with this invention.

Finger 2 is a section on the line 2-2 of Figure 1.

Figure 3 is a section on the line 3-3 of Figure 1.

Figure 4 is a longitudinal section through one modification of the device.

Figure 5 is a similar view of a second modification.

Figure 6 is a similar view of a third modification.

Figure 7 is a side elevation of a modified form of pick point.

In each form of this invention there is provided a tubular handle 10 having a cap 11 at its lower end provided with an opening axially aligned with the handle and having a shank 12 slidable therethrough. All of these shanks are provided at their lower ends with a sharp point 13 forming an ice pick point.

In the form shown in Figs. 1 to 5 the shank is grooved just above the point and a collar 14 is fitted in the groove to receive blows caused by the handle being slid rapidly down the shank.

In Figure 1 the bore of the handle extends

uniformly from end to end thereof and a cap 15 is provided at the upper end of this handle. The shank 12 extends entirely through the handle and passes through a suitable opening in the cap 15. On the upper end of the shank is formed an eye 16 and this eye has a pair of bottle opener lips 17 formed on the part next the handle. A collar 18 is fixed on the shank at the lower end of the handle bore and a spring 19 surrounds the shank and bears at one end on this collar and at its other end on the cap 15.

In the form shown in Figure 4 the bore of the handle terminates in spaced relation to the top and the shank is provided with a collar 20 and spring 21 as before, the spring in this instance bearing at its upper end against the end of the bore. This form is provided with a bottle opener eye 22 having lips 23 and being provided with a pronged shank 24 which is driven into the material of the handle through a suitable opening in a cap 25.

In the forms shown in Figures 5 and 6 the bore of the handle extends from one end to the other thereof but the lower part of this bore is small to fit the shank 12 loosely while the upper part is sufficiently large to accommodate the spring 26 which bears at one end against a collar 27.

In Figure 5 the upper end of the bore is closed by a cap 28 having the shank 29 of a bottle opener eye riveted thereto, the spring 26 bearing against the rivet. This eye is provided with the usual lips 30.

In Figure 6 a plain cap 31 closes the upper end of the handle and the lower part of the shank just above the tapering point is flattened and formed to provide a bottle opener hook 32 which also serves as a collar or stop to receive the blows of the handle.

Figure 7 shows a slight modification of the shank and point wherein the collar 14 is eliminated, the point 13 being shouldered into the shank at 33 to form a stop to receive the handle blows.

In using the device as an ice pick the point is placed on the ice and the handle reciprocated to strike a series of blows on the collar or stop. In using the forms shown in Fig-

ures 1, 4, and 5 as a bottle opener the top of the loop is placed over the bottle cap and the lips caught under an edge of the cap. An upward prying movement on the handle will then remove the cap. It is to be observed that, in Figure 1, the arrangement is such that the handle may be shifted to increase or decrease the leverage by moving from or toward the eye. In the form of Figure 6 10 the handle may also be shifted in this manner and this form is used by placing the point portion on top of the bottle cap, hooking the hook 32 under the cap edge and prying up on the handle.

15 There has thus been provided a simple and efficient device of the kind described and for the purpose specified.

It is obvious that minor changes may be made in the form and construction of the invention without departing from the material spirit thereof. It is not, therefore, desired to confine the invention to the exact form herein shown and described, but it is desired to include all such as properly come within 20 the scope claimed.

Having thus described the invention, what is claimed as new is:

An ice pick including a shank having one end pointed, a wooden handle slidably 30 mounted on said shank and having a longitudinal bore of greater diameter than said shank and extending entirely through the handle, caps each fitted on a respective end of the handle and having an opening therein 35 closely surrounding the shank, said caps fitting on the outside of the ends of the wooden handle to constitute ferrules therefor at each end and thereby to prevent splitting of the handle by blows in either direction, said shank extending through both caps, a collar 40 fixed on the shank within the bore and normally resting against the cap adjacent the shank point, a spring in said bore surrounding the shank and bearing at one end against 45 said collar and at its other end against the cap remote from the point, a striking shoulder on the shank between the first collar and point and adapted to be engaged by the cap upon compression of the spring, and stop 50 means on the remaining end of the shank adapted to engage the other cap upon complete protraction of the pointed end of the shank.

In testimony whereof I affix my signature.

CHARLES LORBER.
